SPEED REGULATING SYSTEM

Elmer E. Woodward, deceased, late of Rockford,
Ill., by Walter T. Woodward, administrator,
Rockford, Ill., assignor to Woodward Governor
Company, Rockford, Ill., a corporation of
Illinois

Application May 19, 1941, Serial No. 394,109

4 Claims. (Cl. 264—7)

This invention relates to speed regulating systems and more particularly to governors equipped with hydraulic compensating or stabilizing mechanism to prevent hunting and having means for modifying the action of the compensating mechanism to compensate for sudden load changes.

One object is to provide in a governor of the above character a novel modifying mechanism which operates more accurately than load compensation heretofore provided.

A more detailed object is to provide a compensation modifying mechanism wherein load changes are detected electromagnetically and utilized through the intermediary of an hydraulic actuator deriving energy from a separate source.

A further object is to provide a load compensator of the above character having an hydraulic servo actuator energized by fluid pressure derived from the pump driven by the prime mover and controlled by a sensitive load detector.

Other objects and advantages of the invention will become apparent from the following detailed description taken in connection with the accompanying drawing which is a schematic view and wiring diagram of a current generating system and governor control embodying the novel features of the present invention.

For purposes of illustration, the invention is shown in the drawing incorporated in an hydraulic governor control for regulating the speed of a water-wheel turbine 6 actuating a generator 7 which supplies electric current to a network 8 on which a load 9 is imposed. The turbine speed is usually regulated by a penstock valve 10 operated through intermediate hydraulic mechanism (not shown) in response to movements of a rod 11 of a servo motor. The latter comprises a piston 12 mounted on the rod 11 and reciprocable in a cylinder 13 and preferably urged in the speed-decreasing direction by a compression spring 14.

As shown, the governor proper comprises a head 15 carrying flyballs 16 and driven from the turbine prime mover 6 through a connection indicated at 17. The flyballs are urged inwardly by a coiled spring 18 which may be adjusted through a screw 19 to vary the governor speed setting. The position of the flyballs determines the axial position of a pilot piston 20 with respect to a port 21 in a sleeve 22 which is slidable axially in a valve body 22* and has a port 23 communicating through a conduit 24 with an accumulator 25. The latter is charged with pressure fluid

5 by a pump 26 driven from the prime mover 6 through the connection indicated at 17. The lower end of the valve cylinder 28 communicates with an oil sump 29 through a port 30 and a passage 31. Pressure fluid flows to and from the upper end of the servo cylinder 13 through a passage 32 connected to the port 21.

10 The mechanism usually employed to compensate for the lag of the prime mover and of the control system so as to prevent hunting includes the sleeve 22 which carries a piston 33 reciprocable in a receiving cylinder 34 and urged by a spring 35 toward a neutral position. A transmitting piston 36 moves with the servo piston 12 to cause oil trapped in the lower end of the piston cylinder 31 to flow to and from the receiving cylinder 34 through a passage 38 having a leak port 39 therein adjustable by a needle 40. The valve chamber communicates with the sump 29 through a pipe 41.

15 The arrangement thus far described is typical of the compensating type of hydraulic governor controls to which the present invention is particularly applicable. In operation, an increase in the turbine speed causes the flyballs to move outwardly lifting the pilot piston 20 and permitting oil to escape to the sump from the servo cylinder through the ports 21 and 30 and the passages 32 and 31. This permits the spring 14 to move the speed controller 11 upwardly which causes closure of the valve 10 and a corresponding decrease in the turbine speed. As an incident to this movement of the servo and transmitter pistons 12 and 36, the pressure in the cylinders 34 and 37 is reduced permitting the piston 33 and the valve sleeve 22 to rise and follow-up the movement of the piston 20. Thus, the port 21 is covered slightly before the normal speed is again attained. Thereafter, oil from the sump 41 is drawn through the valve 38 gradually raising the compensating pressure and permitting lowering of the sleeve to normal position under the action of the centering spring 35.

20 In response to a decrease in speed, the piston 20 is lowered admitting high pressure fluid from the accumulator to the servo cylinder 13 so as to lower the control rod 11 against the action of the spring 14 and increase the turbine speed. This results in an increase in the compensating pressure and immediate lowering of the valve sleeve 22 to close the port 21, gradual restoration of the sleeve to normal position being effected by leakage of fluid to the sump through the valve 39.

Means actuated by power derived from the prime mover 8 and controlled by a sensitive load detector is provided for modifying the pressure in the compensating circuit above described in a manner such as to avoid surges of the prime mover incident to sudden load changes. This means includes a fluid filled cylinder 43 communicating through a conduit 44 with the cylinder 37. A piston 45 in the cylinder 43 is operated in this instance by hydraulic actuator 46 energized from the prime mover driven pump 26 and controlled automatically by a load detector 47. The latter is actuated electrically herein in accordance with changes in the load on the generating system. While the detector, when of electrical character, may comprise a torque motor or the like, a solenoid is employed herein comprising an armature 48 urged in one direction by a spring 49 and in the other direction by a magnetic coil 50. The latter is connected to the secondary of a transformer 51 having its primary interposed in one of the lines leading from the generator 7 so as to be energized constantly. By adjusting a rheostat 53, the change in energization of the solenoid for a given load change may be varied as desired thereby adjusting the amount of load compensation.

The hydraulic actuator 46 comprises a differential piston 54 rigid with the piston 45 and slidable in a cylinder 55. The piston presents an upper surface 56 substantially larger in area than the under surface 57. The lower end of the cylinder 55 is supplied with fluid under constant pressure being in this instance connected through conduits 58 and 59 to the accumulator 25. The constant pressure thus acting on the area 57 continuously urges the pistons 45 and 54 upwardly.

Pressure fluid from the conduit 59 is permitted to flow to the upper end of the cylinder 55 under the control of a valve 60 comprising a plunger 61 slidable in a bore 62 in the piston 45 and a sleeve extension 63 thereof. The plunger 61 coacts with ports 64 connecting the upper end of the cylinder with the bore 62 which is connected through ports 65 with the conduit 59. A hole 67 through the pistons 45 and 54 and a lower extension 68 permits the escape of fluid to a drain when the valve member is raised above the ports 64.

The stem 66 of the valve member is rigid with the solenoid armature 48 so that the valve member 61 is raised and lowered as the load on the prime mover increases and decreases. Because the fluid pressure on the valve member 61 is balanced by the same pressure on the piston 69, it will be observed that the valve member is unrestrained and may be moved easily by the solenoid. Accordingly, the valve member is positioned rapidly and accurately in response to load changes detected by the solenoid.

Assuming the parts to be in equilibrium as shown, the load compensating control produces its anticipating corrective action in the following manner in response to a sudden increase in load. Such a change results in a corresponding increase in the current energizing the solenoid coil 50 drawing the plunger 48 and the valve member 61 upwardly against the compression of the spring 49. This uncovering of the ports 64 permits fluid to drain from the upper end of the cylinder. The resulting reduction in pressure permits the pistons 45 and 57 to rise under the predominant upward pressure on the piston area 57. During its upward move-

ment, the piston 45 draws oil out of the transmitting cylinder 37, the consequent lowering of the pressure in the receiving cylinder 34 permitting the valve sleeve 22 to rise relative to the valve piston 20. Pressure fluid thus flows from the accumulator 25 into the power cylinder 13 and the servo piston 12 moves downwardly so as to start increasing the speed setting of the prime mover controller before the flyballs have detected a drop in speed. This action tends to minimize the speed change resulting from a load change.

The reverse action occurs upon a sudden decrease in load which causes the pull of the solenoid 50 to be decreased and the valve member 61 to be lowered thereby admitting pressure fluid from the supply line 59 to the upper end of the cylinder 55. As a result of the increased pressure above the piston 54, the piston 45 is moved downwardly thus forcing oil into the compensating system and lowering the piston 33 so as to permit the passage of oil from the power cylinder 13 to the sump. The spring 14 then moves the control rod 11 in the spaced decreasing direction in anticipation of the speed change that would normally result from the load reduction.

It will be observed that the load compensator produces the same action of the governor pilot valve as the flyballs would produce in the absence of the load detector. This action occurs in advance of the time that the flyball action would otherwise occur and therefore is of anticipatory character so as to compensate for the inherent lag in the response of the governor and reduce surges of the prime mover that normally take place under sudden load changes. The load compensator in effect supplements the regular governor control which operates in the normal way to correct for gradual speed changes. Owing to the leakage through the valve 39 following the pressure changes instituted by the electric load change detector, the action of the latter is of temporary character and does not produce a permanent shift in the control point of the governor.

The claimed invention is:

1. The combination with a prime mover of a governor operable in unison with and controlling the speed of said prime mover, an hydraulic system associated with said governor to produce a compensating action in response to speed adjustments, two axially aligned cylinders of different diameters, a hollow piston slidable in the smaller cylinder and having a flange slidable in the larger cylinder, means connecting said smaller cylinder with said hydraulic system, a tubular extension projecting from the flanged end of said piston and providing a valve chamber communicating with the remote end of the larger cylinder, means applying a substantially constant fluid pressure to the other end of the larger cylinder, a tubular extension projecting from the smaller end of said piston and providing a drain outlet, a valve member reciprocable in said first extension and regulating the flow of pressure fluid therefrom into said larger cylinder, and means operable automatically to vary the position of said valve member in accordance with load changes on said prime mover.

2. The combination with a prime mover of a governor operable in unison with and controlling the speed of said prime mover, an hydraulic system associated with said governor to produce a compensating action in response to speed adjustments, two cylinders of different diameters

disposed end to end, connected pistons slidable in said cylinders and having a passage extending through the two cylinders and providing a valve chamber communicating with the outer end of the larger cylinder and a drain outlet at the other end, means connecting the smaller cylinder to said hydraulic system, means applying a substantially constant fluid pressure to the inner end of the larger cylinder, a valve member in said chamber regulating the flow of pressure fluid therefrom into said larger cylinder, and means operable automatically to vary the position of said valve member in accordance with load changes on said prime mover.

3. The combination with a prime mover of an hydraulic governor operable in unison with said prime mover and having a speed responsive valve and a servo motor controlled by said valve and modulating the speed of said prime mover, hydraulically connected transmitting and receiving cylinders having a leak valve outlet, pistons in said cylinders respectively connected to said servo motor and said valve so as to impart a compensating adjustment to the valve as an incident to speed adjustment of said prime mover, a third cylinder communicating at one end with said first mentioned cylinders and having a piston therein, a fluid pump adapted to deliver a counteracting hydraulic pressure to the other side of said third piston, valve means variably controlling the magnitude of said counteracting pressure, and means automatically responsive to changes in the load on said prime mover for variably positioning said valve means.

5 counteracting hydraulic pressure to the other side of said third piston, and means automatically responsive to changes in the load on said prime mover for variably controlling the magnitude of said last mentioned pressure.

4. The combination with a prime mover of an hydraulic governor operable in unison with said prime mover and having a speed responsive valve and a servo motor controlled by said valve and modulating the speed of said prime mover, hydraulically connected transmitting and receiving cylinders having a leak valve outlet, pistons in said cylinders respectively connected to said servo motor and said valve so as to impart a compensating adjustment to the valve as an incident to speed adjustment of said prime mover, a third cylinder communicating at one end with said first mentioned cylinders and having a piston therein, a fluid pump adapted to deliver a counteracting hydraulic pressure to the other side of said third piston, valve means variably controlling the magnitude of said counteracting pressure, and means automatically responsive to changes in the load on said prime mover for variably positioning said valve means.
